APPARATUS FOR TREATING TUBULAR
PACKAGES OF THREAD OF FINE FILA-
MENTOUS CHARACTERCharles A. Huttinger, Lakewood, Ohio, assignor
to Acme Rayon Corporation, Cleveland, Ohio,
a corporation of Ohio

Application December 23, 1938, Serial No. 247,453

3 Claims. (CL. 58—198).

My invention relates to the treatment of fine filamentous thread, and particularly to the fluid treatment of thread of this character in tubular package form, such as rayon cakes, spools, etc. 5 These fluid treatments are purifying and other operations to which rayon is necessarily subjected, before the precipitated and package-collected thread can be considered a final product ready for the market, such treatments including 10 various water washings, desulphurizing, bleaching, oiling, sizing, dyeing, drying, and other purifying and finishing operations. The particular objects of the invention are to provide economical and reliable apparatus for effecting these fluid 15 treatments, apparatus which will function without discoloring or otherwise contaminating the thread, and which will permit suitable loosening up of the freshly-spun packages by the fluid treatment so as to provide for all parts of the 20 package their respective scopes of natural free play, relative to other parts of the package, without injuriously disarranging the thread or the multiple filaments of which the thread is comprised. 25 The annexed drawings and the following description set forth in detail certain means illustrating my improved apparatus, such means constituting, however, only a few of the various forms in which the principle of the improved apparatus may be embodied.

In said annexed drawings:

Figure 1 is a fragmentary vertical section through a treatment tank and means for supporting the same and supplying treating fluid to and conveying treating fluid from the tank, in which tank is positioned a vertical tier of axially aligned thread packages mounted on outwardly-extended flanges of improved package inserts forming part of my invention, the packages being shown in Figure 1 in their freshly-spun condition before fluid treatment; 40

Figure 2 is a horizontal section, taken in the plane indicated by the line 2—2, Figure 1;

Figure 3 is a fragmentary view, similar to Figure 1, but showing the thread packages in the condition taken on, and the position assumed, during the treating operation;

Figure 4 is a horizontal section, taken in the plane indicated by the line 4—4, Figure 3;

Figure 5 is a partial elevation and a partial vertical section, upon an enlarged scale, of the upper part of the package insert and supporting means shown in Figure 1, the view being taken in the planes indicated by the line 5—5, Figure 6;

Figure 6 is a horizontal section, taken in the plane indicated by the line 6—6, Figure 5;

Figure 7 is a fragmentary view, upon an enlarged scale, of certain elements of a top insert forming a cap member for a tier of inserts, 5 these elements being shown in the upper right hand corner of Figure 5;

Figure 8 is a view, upon an enlarged scale, of a fragmentary portion of Figure 5, showing particularly the means for mounting the cap 10 member for the tier of inserts upon the topmost insert of the tier;

Figure 9 is a view, upon an enlarged scale, of a fragmentary portion of Figure 5, showing particularly the means for mounting an insert of 15 a tier upon the insert adjacently below; and

Figure 10 is a fragmentary vertical section, upon an enlarged scale, illustrating the method for securing to an insert an outwardly-extended flange forming a package support and also serving as a separator between the contiguous ends 20 of vertically-adjacent packages of a tier.

Referring to the annexed drawings, in which the same parts are indicated by the same respective numbers in the several views, my improved apparatus includes a plurality of tubular frusto-conical axially-aligned columns forming package inserts 1 and each having secured thereto, and adjacent one end thereof, an outwardly-extended flange 2 forming a package support. These package supports 2 also serve as spacers between vertically-adjacent packages. This package support 2 is formed with an up-turned peripheral edge 3. Upon the flange 2 a frusto-conical tubular rayon package 4 is mounted, being retained 30 in position thereon by the up-turned edge 3, the diameter of the inner face of the package 4 being materially greater than that of the outer surface of the insert 1 so that an annular space 11 is provided between the outer face of the insert 1 and the inner face of the package 4, in which space 11 the tubular package 4, under the fluid treatment, may expand inwardly and become loosened and hence more porous, as illustrated by the treated packages shown in Figure 3. 40

By means hereinafter fully described, a plurality of the inserts 1 are formed into an axially-aligned vertical tier of communicating inserts, and the tier mounted upon a soft rubber seat 5 having a port 9 therethrough formed with enlarged outer end portions 9¹ and 9² serving to receive fluid from comparatively large areas. The soft rubber seat 5 is in turn mounted upon and secured in a main base 14 through which treating fluid passes to and from the central chamber 55

22 formed by the tier of communicating inserts 1, the port 9 communicating with a port 14' formed in the top of the main base 14.

It will be understood that there are treated in 5 any one operation any suitable number of suitably spaced and arranged tiers of rayon packages, of which one tier only is shown for illustration in Figure 1.

The inserts 1 are each provided with a multiplicity of ports 8. Therefore, it is evident, that treating fluid can be passed from the base 14 through the ports 14' and 9 into the central chamber 22 formed by the communicating inserts and thence outwardly through the ports 8 into the spaces 11, whence it passes through the rayon packages 4. Likewise, treating fluid can be passed from without the packages 4 through the same and into the space 11 and thence through the ports 8 and the central chamber 22 and the ports 9 and 14' and outwardly through the base 14. This fluid treatment is effected in a suitable treatment tank 13, which also is mounted upon the base 14 and secured thereto by a peripheral angle 13² which is welded to the bottom of the sides of the tank 13.

25 Any suitable number of laterally-spaced tiers of inserts 1 and supported packages 4 may be mounted in the tank 13 upon the base 14 and the inserts of the several tiers are locked together into compact formations by a suitable 30 plate 6 mounted upon a peripheral rubber pad 7 superimposed upon a peripheral angle 13' welded to the side of and adjacent the top of the tank 13, the plate 6 being actuated by any suitable 35 clamping means 23.

35 By means of communicating ports (not shown) in the bottom of the tank 13 and in the top of the base 14, the treating fluid can be passed from the space 24 in the tank 13, between and around the several package tiers; i. e., the space 40 in the tank 13 outside of the packages 4, outwardly of the tank 13, or passed into the space 24 through such ports, dependent upon the direction of flow of the treating fluid, whence it passes to the source of supply through the base 14, or 45 passes through the bodies of the packages 4 into the spaces 11. This structure of tank and base ports and means for reversing liquid flow are well known and a showing thereof is not required for an adequate understanding of the instant invention. An overflow lip for the treating fluid from the tank 13 intermediate the tiers of inserts is indicated in Figure 1.

In order to insure that the topmost packages of the tiers of packages shall be adequately covered with the treating fluid, I provide an extended top insert forming a suitable cap member 10 for each tier of inserts 1, the same being completely closed except that it is open at its bottom end which is of a formation similar to that 55 of the bottom of an insert 1. This cap member 10 is of cylindrical formation having a cross-section equal to that of the larger end of an insert 1 and is supported upon the topmost insert 1 of the tier and communicates through its open bottom therewith.

65 I provide improved means for supporting the cap member 10 upon the tier of inserts, for mounting the inserts 1 one upon the other, and for securing the package-supporting and separating flanges 2 to the inserts 1. The insert and cap supports are formed by punching inwardly the material of the bodies of the inserts and the cap somewhat inwardly of one end thereof, the large end in the case of the inserts 1, so as to 70 form a horizontal series of spaced tongues 18, as

clearly shown in Figures 8 and 9, whereby the insert or cap may be supported by said tongues 18 upon the top of the insert adjacently below, the frusto-conical formation of the insert 1 permitting the smaller end thereof to be inserted into the larger end of the insert adjacently above, or into the cap member 10, as clearly shown in the accompanying drawings and particularly in Figures 8 and 9.

The inserts 1 and supporting flanges 2 and cap member 10 are formed of stainless steel. I secure the inserts 1 and the cap member 10 to the flanges 2 by the improved means now to be described. The same means also apply to the securing of a cover member 10' to the top of the 15 cap member 10, as shown in Figure 7. The inserts 1 and cap members 10 are formed with horizontal series of holes 15 therethrough adjacent one end of each of the inserts 1 and adjacent both ends of the cap member 10. An upturned inner edge 16 of a flange 2 is forced over the larger end of an insert 1 or one end of the cap member 10 and material 17 of the edge 16 punched into the holes 15 formed in the insert 1 and cap member 10, as clearly shown in Figure 20 25 10. The cover member 10' is secured to the top of the cap member 10 in like manner, Figure 7, by means of a downwardly-extended flange 10², holes 15, and material 10³. It will be noted that the terminal portion 21 of the inner edge 16 of 30 the topmost flange or separating member 2 is crimped inwardly against the body of the tongues 18, Figure 8, in order more securely to mount and center the cap member 10 and to render this joint substantially water-proof.

I direct particular attention to the fact that the supporting and separating flanges 2 are vertically spaced apart a distance somewhat greater than the height of one of the untreated packages 4, thus leaving a slight space 19, Figure 1, between the top of the package 4 and the bottom of the adjacently higher flange 2. This space 19 permits the package 4 to elongate somewhat during the fluid treatment and engage the lower face of the adjacently upper flange 2, as clearly shown 45 in Figure 3. The package 4 does not substantially increase its outer diameter during the fluid treatment; in fact, it becomes somewhat smaller in outer diameter, as indicated by the spaces 20, Figure 3, between the outer faces of the treated 50 packages 4 and the upturned flange edges 3, which spaces 20 are relatively larger than the corresponding spaces in Figure 1. The increase in thickness in the body of the packages takes place inwardly so that the packages when the 55 fluid treatment is completed practically fill the spaces 11, but they do not tightly engage the outer faces of the inserts 1, as is indicated by the resultant final small space 12, Figure 3, due to which and the conical structure of the inserts it 60 is possible easily to remove the treated packages from the inserts 1.

As stated, the inserts 1, flanges 2, and cap members 10 are made of stainless steel and, in order that the other parts of the apparatus may 65 be rendered non-corrosive, the exposed surfaces of the tank 13 and angles 13' and 13² are provided with rubber liners; as also, the bottom face of the locking member 6 and the exposed surfaces of the base 14, all as clearly shown in Figure 1.

What I claim is:

1. A package insert for treating a tubular package of thread of fine filamentous character consisting of a ported frusto-conical tubular 70 75

column having package-supporting means, and spaced inwardly-projected insert-supporting tongues formed from the body of the column adjacent the larger end of the latter and serving 5 also to nest the insert with another like insert.

2. In apparatus for treating tubular packages of thread of fine filamentous character, a ported tubular column having package-supporting means, and a cap member having package-spacing means adjacent its lower end, said cap member also having a bottom opening communicating with the chamber of the column, the cap member being formed with spaced inwardly-projected tongues adjacent its open end by which it is supported upon one end of the column. 10

15 3. In apparatus for treating tubular packages

of thread of fine filamentous character, a ported tubular column having package-supporting means, and a cap member having a bottom opening communicating with the chamber of the column, the cap member being formed with spaced inwardly-projected tongues adjacent its open end by which it is supported upon one end of the column, the cap member also having a transverse series of spaced holes therethrough and a laterally-projected package-spacing flange 5 having an upturned edge portion secured to the cap member by material thereof forced into the series of holes, the terminal of the upturned edge portion being crimped against the tongues. 10
